UNITED STATES PATENT OFFICE.

GUSTAF A. HERMANSON, OF CHICAGO, ILLINOIS, ASSIGNOR TO JAMES MUNTON, OF MAYWOOD, ILLINOIS.

CAR-COUPING.

No. 830,715.

Specification of Letters Patent.

Patented Sept. 11, 1906.

Application filed April 2, 1906. Serial No. 809,251.

To all whom it may concern:

Be it known that I, GUSTAF A. HERMANSON, a citizen of the United States, residing in Chicago, in the county of Cook and State of Illinois, have invented a new and useful Improvement in Car-Couplers, of which the following is a specification.

My invention relates to improvements in car-couplers of the Master Car-Builders' type, having a forked draw-head, pivoted knuckle, and vertically-movable lock.

In Master Car-Builders' couplers heretofore in use the lock is not adapted to be lifted or the cars uncoupled while the knuckle is under tension or strain, it being necessary to produce slack between the coupled cars and relieve the knuckle from strain or tension before the lock can be moved or lifted, and this in practical operation frequently causes inconvenience and delay; and it is the object of my invention to furnish a Master Car-Builders' coupler of a simple, strong, efficient, safe, reliable, and durable construction in which the lock may be lifted and the cars uncoupled while the knuckle is under tension or strain, so that it will not be necessary to produce slack in the train to relieve the knuckle from tension in order to lift the lock and uncouple cars, as has heretofore been the case.

My invention consists in the means I have devised and employ to accomplish this result—that is to say, it consists, in connection with the draw-head and knuckle, of any suitable construction, of a movable lock having a tapering or wedging lower end and provided with a coöperating wedging extension slidably connected with the lock, the lock and draw-head being provided with coöperating locking-shoulders to hold the lock in place and from creeping upward, and a movable keeper, preferably hinged to the lock near its upper end and adapted to engage a projection or ledge on the draw-head to keep the locking-shoulders on the draw-head and lock normally in engagement with each other, the clevis of the lifting-lever serving to unlatch or disengage the keeper at the initial lifting movement and the inclined or wedging end of the lock enabling it to be raised while under tension of the draw-head and knuckle.

My invention also consists in the novel construction of parts and devices and in the novel combinations of parts and devices herein shown and described.

55 In the accompanying drawings, forming a

part of this specification, Figure 1 is a side elevation, partly in central vertical longitudinal section, of a car-coupler embodying my invention. Fig. 2 is a cross-section on line 2 2 of Fig. 1. Fig. 3 is a detail view of the lock. Fig. 4 is a detail view of the lock extension. Fig. 5 is a horizontal section on line 5 5 of Fig. 1; and Fig. 6 is a view similar to Fig. 2, showing a modification.

In the drawings, A represents the draw-bar; A', the draw-head, having the customary guard-arm a' and pivot-arm a.

B is the knuckle, having the customary front arm or nose b and rear arm or tail b'; C, the pivot-pin; D, the lock; F, the movable keeper for the lock; G, the lifting-lever, and G' the clevis connecting the lifting-lever with the lock and the keeper.

The lock D is furnished with an incline or wedging portion d, preferably at or near its lower end, engaging a coöperative incline or wedging portion d', preferably on a separate-piece extension D' of the lock, which is slidably connected with the lock D, preferably by an interengaging slot d² on the one part 80 and hook or projection d³ on the other part, the slot being preferably in the lock and the projection in the separate-piece slidably extension D' of the lock. The angle of these coöperating inclines or wedging portions is 85 such that when the lock is under tension of the knuckle, as illustrated in Fig. 5, the lock can be readily lifted, the strain of the knuckle upon the lock either tending normally to raise the lock or so nearly approaching a neutral tendency as to enable the lock to be readily raised by the lifting-lever while the lock is under tension. The angle of these coöperating inclines may be so adjusted as to permit the lock to be raised by the lifting-lever while it is under partial tension or strain of the knuckle and prevent its being so lifted when the lock is under full strain or tension of the knuckle, as it ordinarily is not desired to uncouple the cars while the couplers are under full strain or load of the train, although it is very desirable that the coupler should be capable of uncoupling the cars when the same are under partial strain or tension, so that the brakeman will not have to wait until each coupler is entirely loose and free from strain before he can lift the lock and effect an uncoupling.

To hold my under-tension uncoupling-lock securely in position and prevent all danger of 110

its being lifted or crowded upward by reason of the tension of the knuckle on its incline or wedging portion, I provide the draw-head and lock with interengaging locking-shoulders a^2 and d^5 , the latter being on the front side of the lock and adapted to be disengaged from the coöperating shoulder a^2 on the draw-head by the initial backward movement of the upper end of the lock when the same is to be raised by the lifting-lever.

To hold the coöperating shoulders a^2 on the draw-head and lock normally in engagement with each other, I provide the lock with a rocking or movable keeper F, having a lip 15 or hook f engaging a coöperating lip a^3 on the draw-head, and to which the clevis G' of the lifting-lever G is directly connected, preferably by the clevis-pin g' , and which has a sliding or loose connection d^6 with the lock, 20 this sliding or loose connection preferably consisting simply in an upright slot in the lug d^7 of the lock. The first movement of the lifting-lever and clevis thus unlatches or disengages the keeper F from the draw-head 25 and permits the lock to then tilt backward when pulled upon by the lifting-lever, and thus disengage the locking-shoulders d^5 and a^2 from each other, so that the lock can be lifted and so that the incline or wedging portion 30 d of the lock may enable the lock to be lifted while it remains under tension of the knuckle to a greater or less extent.

The rear end f^2 of the keeper F may preferably fulcrum upon the cap or flange d^8 of the lock. This cap or flange is preferably inclined, and the upper face a^4 of the draw-head, against which this lock cap or flange fits, is also preferably forwardly and downwardly inclined, so that the upper end of the 40 lock will normally tilt or move forward.

The lock D or its separate-piece extension D' may preferably be furnished with the customary lock-set shoulders or ledges d^9 d^{10} to engage the draw-head or knuckle-tail and 45 set or hold the lock in position for coupling or uncoupling.

In the modification illustrated in Fig. 6 the lock is made in one piece, and the separate-piece extension D' is omitted, and the incline or wedging portion which coöperates with the incline or wedging portion d on the lock is formed on the draw-head itself instead of upon a separate-piece extension of the lock. In Fig. 6 the coöperating incline 55 or wedging portion is marked d^{11} .

I claim—

1. In a car-coupler, the combination with a draw-head and knuckle, of a movable lock having an incline or wedging portion engaging a coöperating incline or wedging portion to enable the lock to be released and raised when the knuckle bearing against the lock is under tension, coöperating locking-shoulders on the draw-head and lock to hold the lock 65 normally closed, and a movable keeper to

hold the locking-shoulders on the lock and draw-head normally in engagement, said movable keeper having a loose connection with the lock to cause it to be unlatched or disengaged by the initial movement of the lifting-lever or its clevis, substantially as specified. 70

2. In a car-coupler, the combination with a draw-head and knuckle, of a movable lock having an incline or wedging portion engaging a coöperating incline or wedging portion to enable the lock to be released and raised when the knuckle bearing against the lock is under tension, coöperating locking-shoulders on the draw-head and lock to hold the lock 75 normally closed, and a movable keeper to hold the locking-shoulders on the lock and draw-head normally in engagement, said movable keeper having a loose connection with the lock to cause it to be unlatched or disengaged 80 by the initial movement of the lifting-lever or clevis, said coöperating incline or wedging portion being on a separate-piece extension of the lock, substantially as specified. 85

3. In a car-coupler, the combination with a draw-head and knuckle, of a movable lock having an incline or wedging portion engaging a coöperating incline or wedging portion to enable the lock to be released and raised when the knuckle bearing against the lock is 90 under tension, coöperating locking-shoulders on the draw-head and lock to hold the lock normally closed, and a movable keeper to hold the locking-shoulders on the lock and draw-head normally in engagement, said movable keeper having a loose connection with the lock to cause it to be unlatched or 95 disengaged by the initial movement of the lifting-lever or clevis, said coöperating incline or wedging portion being on a separate-piece extension of the lock, and said separate-piece extension having a sliding connection 100 with the lock, substantially as specified. 105

4. In a car-coupler, the combination with the draw-head and knuckle, of a movable lock having an incline or wedging portion, a separate-piece extension of the lock having a sliding connection with the lock and provided with a coöperating incline or wedging portion, to enable the lock to be raised when under tension of the knuckle and means for holding the lock in its normal or closed position, substantially as specified. 115

5. In a car-coupler, the combination with the draw-head and knuckle, of a movable lock having an incline or wedging portion, separate-piece extension of the lock having a sliding connection with the lock and provided with a coöperating incline or wedging portion to enable the lock to be raised when under tension of the knuckle, means for holding the lock in its normal or closed position and means for releasing said holding means, substantially as specified. 125

6. In a car-coupler, the combination with a 130

draw-head and knuckle, of a movable lock having a tapering or wedging portion to enable the lock to be released and raised when the knuckle bearing against the lock is under tension, the lock and draw-head having inter-engaging locking-shoulders to hold the lock in its normal or closed position, and a movable keeper for holding said locking-shoulders normally in engagement, substantially as specified.

7. In a car-coupler, the combination with a draw-head and knuckle, of a movable lock having a tapering or wedging portion to enable the lock to be released and raised when the knuckle bearing against the lock is under tension, the lock and draw-head having inter-engaging locking-shoulders to hold the lock in its normal or closed position, and a movable keeper for holding said locking-shoulders normally in engagement, said movable keeper having a loose or sliding connection with the lock, and a lifting-lever connected to the keeper, substantially as specified.

8. In a car-coupler, the combination with a draw-head and a pivoted knuckle, of a movable lock having a tapering or wedging lower end to enable the lock to be released and raised when the knuckle bearing against the lock is under tension, said lock being provided with a separate-piece extension having a tapering or wedging upper end bearing against the wedging or tapering lower end of the lock, substantially as specified.

9. In a car-coupler, the combination with a draw-head and a pivoted knuckle, of a movable lock having a tapering or wedging lower end to enable the lock to be released and raised when the knuckle bearing against the lock is under tension, said lock being provided with a separate-piece extension having a tapering or wedging upper end bearing against the wedging or tapering lower end of the lock, said separate-piece extension having a loose or sliding connection with the lock, substantially as specified.

10. In a car-coupler, the combination with a draw-head and a pivoted knuckle, of a movable lock having a tapering or wedging lower end to enable the lock to be released and raised when the knuckle bearing against the lock is under tension, the draw-head having a shoulder or projection to prevent the lock from creeping, and the lock having at its upper end a coöperating shoulder engaging said shoulder on the draw-head to prevent the lock from creeping, substantially as specified.

11. In a car-coupler, the combination with a draw-head and a pivoted knuckle, of a movable lock having a tapering or wedging lower end to enable the lock to be released and raised when the knuckle bearing against the lock is under tension, said lock being provided with a separate-piece extension having a tapering or wedging upper end bearing against the wedging or tapering lower end of

the lock, the draw-head having a shoulder or projection to prevent the lock from creeping and the lock having at its upper end a coöperating shoulder engaging said shoulder on the draw-head to prevent the lock from creeping, substantially as specified.

12. In a car-coupler, the combination with a draw-head and a pivoted knuckle, of a movable lock having a tapering or wedging lower end to enable the lock to be released and raised when the knuckle bearing against the lock is under tension, the draw-head having a shoulder or projection to prevent the lock from creeping, and the lock having at its upper end a coöperating shoulder engaging said shoulder on the draw-head to prevent the lock from creeping, and a movable keeper on the upper end of the lock engaging a projection on the draw-head to hold said creeper-prevention shoulders on the lock and draw-head in engagement, substantially as specified.

13. In a car-coupler, the combination with a draw-head and a pivoted knuckle, of a movable lock having a tapering or wedging lower end to enable the lock to be released and raised when the knuckle bearing against the lock is under tension, said lock being provided with a separate-piece extension having a tapering or wedging upper end bearing against the wedging or tapering lower end of the lock, said tapering-piece extension having a loose or sliding connection with the lock, the draw-head having a shoulder or projection to prevent the lock from creeping, and the lock having at its upper end a coöperating shoulder engaging said shoulder on the draw-head to prevent the lock from creeping, substantially as specified.

14. In a car-coupler, the combination with a draw-head and a pivoted knuckle, of a movable lock having a tapering or wedging lower end to enable the lock to be released and raised when the knuckle bearing against the lock is under tension, said lock being provided with a separate-piece extension having a tapering or wedging upper end bearing against the wedging or tapering lower end of the lock, said separate extension having a loose or sliding connection with the lock, the draw-head having a shoulder or projection to prevent the lock from creeping, and the lock having at its upper end a coöperating shoulder engaging said shoulder on the draw-head to prevent the lock from creeping, and a movable keeper on the upper end of the lock engaging a projection on the draw-head to hold said creeper-prevention shoulders on the lock and draw-head in engagement, substantially as specified.

GUSTAF A. HERMANSON.
